UNITED STATES PATENT OFFICE

LYDIA B. KOCH, OF NEW YORK, N. Y.

CLOSURE CAP FOR PAPER MILK BOTTLES

Application filed May 21, 1930, Serial No. 454,295. Renewed October 15, 1932.

My invention relates to improvements in closure caps for paper milk bottles and the object of the invention is to devise a closure cap which is especially adaptable for a type of bottle having a tapered upper portion longitudinally corrugated from midway of its length into the flange of its neck.

A further object is to make such a cap as will interfit into the corrugations externally. 10 A still further object is to provide in a cap means whereby a portion of its contents may be poured out directly or withdrawn through a straw without removing the cap itself and yet the cap sealed so as to close the openings 15 and prevent contamination of the remainder of the contents.

To effect these objects my cap is provided with a depending corrugated portion adapted to fit the corrugations of the flange and 20 upper tapered portion of the body and a dished central portion concavo-convex in cross-section, having diametrically located orifices provided with pouring lips and a curved strip suitably pivoted and adapted to 25 fit the concavo-convex top and to close or uncover the orifices as may be desired and as hereinafter more particularly explained.

Fig. 1 is a perspective view of the upper portion of a paper milk bottle provided with 30 my closure cap.

Fig. 2 is a vertical section through the extreme upper portion.

Fig. 3 is a sectional perspective detail of the cap.

Fig. 4 is a sectional plan through the cap and upper tapered portion showing the relative position of the cap and corrugated portion when the cap is closed.

Fig. 5 is a similar plan view showing the cap given a slight turn so as to cause the in-turned ribs of the corrugations to ride on the outturned corrugations of the neck at the upper end of the tapered portion.

In the drawing like characters of reference indicate the corresponding parts.

1 is the upper portion of a milk bottle which is made of paper of a suitable thickness. The portion 1 is tapered from a point about midway of the height of the bottle and is provided with corrugations 2 made

up of the longitudinal depressions 3 and the ribs 4, such depressions and ribs narrowing from the bottom to the top and terminating in a neck portion 5 formed as described in a former application by inturning the top edge of the tapered portion by spinning and swedging to form an internal seat 6 and an upstanding portion 7. 55

8 is the cap which is made with a depressed or dished central portion 9 in concavo-convex form and having the inner edge 10 resting on the seat 6. 60

The cap 8 is provided with an outer rim 11 which extends over the upstanding portion 7 and down over the outside of the flange forming the neck as indicated in Figs. 1 and 2, where it forms a skirt 12 which is corrugated as shown. The ribs of such corrugations are designated 13 and the depressions 14. These ribs and depressions correspond with the ribs 4 and depressions 3 over which they are designed to fit when the cap is set in position. 70

Being made of paper, having a certain amount of resiliency, the cap may be forced 75 home although its lower corrugated edge may be slightly less in diameter than the outside diameter of the upstanding portion 7 of the neck. But when forced home it will necessarily cling to the tapered portion immediately underneath the neck, the ribs and depressions of the cap interfitting with the ribs and depressions of the upper portion of the bottle. 80

It will thus be seen that the cap will be securely held in position for ordinary usage but may be readily removed by grasping the rim 11 with the hand and pulling upwardly thereon or it may be preferable to give the cap a slight twist with the hand so as to throw it around sufficiently in order to cause the inwardly extending ribs formed by the depressions 14 of the cap to ride on the ribs 4 as indicated in Fig. 5, whereby the cap may be spread sufficiently outwardly so that 85 it may be withdrawn easily. 90

The cap 8 as far as now described is a complete closure and when removed enables, if it is desired, the complete contents of the bottle to be discharged. 100

If, however, it is desired to withdraw only a portion of the contents I have provided in the concavo-convex portion 9 two openings 15 diametrically located opposite each other 5 and lips 16 depressed or otherwise formed out of the concavo-convex portion 9 beneath the openings 15.

These openings are normally closed by a bridge strip 17 pivoted at 18 centrally. By 10 swinging the bridge strip, which follows the curve of the concavo-convex portion 9, around a sufficient distance the openings 15 may be uncovered and the milk poured out through the openings 15, the lips 16 forming 15 a guide for directing the milk clear of the rim 11.

If desired, however, a straw may be inserted through the openings 15 and the milk withdrawn thereby.

20 The openings 15 are only utilized when it is desired to withdraw only a portion of the contents of the bottle and reseal it. When it is desired to remove the whole of the contents, of course, the cap would be removed 25 altogether.

Such a cap as I describe forms a strong and complete closure, not liable to come off except it is removed by the hand or other means.

30 In practice I prefer to coat the cap with paraffin and place it in position when it is warm, so by this means I provide a perfect seal both at the seat as well as on the exterior of the flange surrounding the same.

35 What I claim as my invention is:

1. A closure cap for milk bottles comprising a circular top dished so as to provide an annular hollow flange with the outer flange which depends around the neck formed at 40 the upper end of the tapered portion and is provided with circumferential corrugations designed to register, fit into, interlock and grip the corrugations in the upper portion of the bottle.

45 2. A closure cap for milk bottles comprising an outer rim having a depending portion adapted to grip the flange of the neck, and a central concavo-convex dished portion provided with diametrically located openings 50 having depending lips and a bridge strip centrally pivoted and following the contour of the concavo-convex portion and adapted normally to cover the openings and to be swung to uncover them.

55 3. The combination with a paper milk bottle provided with a corrugated upper portion terminating in a circumferential flange at the top having an inwardly extending seat, of a closure cap having a hollow rim formed 60 by a dished portion and depending flange, such flange being corrugated circumferentially in its lower portion and adapted to fit the corrugations of the tapered portion beneath the flange of the neck.

65 4. A closure cap for milk bottles compris-

ing a circular top dished so as to provide an annular hollow flange with the outer flange which depends around the neck formed at the upper end of the tapered portion and is provided with circumferential corrugations designed to register, fit into interlock and grip the corrugations in the upper portion of the bottle, and resiliently extend under the exterior neck flange when the cap is in position.
